(57) **CLAIM**

The ornamental design for a winder for launching apparatus for spinning top toy, as shown.

DESCRIPTION

FIG. 1 is a front view of the winder for launching apparatus for spinning top toy showing my design;

FIG. 2 is a left side view thereof;

FIG. 3 is a rear view thereof;

FIG. 4 is a right side view thereof;

FIG. 5 is a top view thereof;

FIG. 6 is a bottom view thereof;

FIG. 7 is a front perspective view thereof;

FIG. 8 is a rear perspective view thereof; and,

FIG. 9 is a cross-sectional view taken along line 9-9 of FIG. 1.

1 Claim, 9 Drawing Sheets(56)
